UNITED STATES PATENT OFFICE.

ROBERT E. BOYLE, OF NORRISTOWN, PENNSYLVANIA.

DESIGN FOR A GAME-BOARD.

SPECIFICATION forming part of Design No. 29,081, dated July 19, 1898.

Application filed June 22, 1898. Serial No. 684,185. Term of patent 14 years.

To all whom it may concern:

Be it known that I, ROBERT E. BOYLE, a citizen of the United States, residing at Norristown, in the county of Montgomery and 5 State of Pennsylvania, have invented and produced a new and original Design for a Game-Board, of which the following is a specification, reference being had more particularly to the accompanying drawing, illustrating the same and forming part hereof.

The leading feature of my design comprises the game-board made the subject of illustration and description, and which consists of a raised margin or edge surrounding a generally rectangular base, and a figure resembling a St. Andrews cross displayed in raised outline upon said base, and a split ring displayed in relief at or near the center of the cross, which is somewhat enlarged for its accommodation.

20 In the drawing, *a* is the raised margin or

edge, *b* the base, and *c* the figure of the cross of St. Andrews in raised outline, two of the arms *c'* and *c''* being open at their extremities, as shown.

d is the split ring in relief, the split being 25 indicated at *d'*.

The relative arrangement of the various parts is best understood by reference to the drawing, which shows a perspective view of the game-board.

30 What I claim as my invention, and desire to secure by Letters Patent, is—

The design for a game-board, substantially as shown and described.

In testimony whereof I have hereunto 35 signed my name.

ROBERT E. BOYLE.

In presence of—

C. S. SHEIVE,
GILLET W. FOX.
